ATTORNEY.

UNITED STATES PATENT OFFICE.

ROBERT J. HOPPINGER, OF CLEVELAND, OHIO.

LOOSE-LEAF BINDER.

1,108,438.

Specification of Letters Patent. Patented Aug. 25, 1914.

Application filed April 2, 1913. Serial No. 758,324.

To all whom it may concern:

Be it known that I, ROBERT J. HOPPINGER, a citizen of the United States, residing at Cleveland, in the county of Cuyahoga and State of Ohio, have invented a new and useful Improvement in Loose-Leaf Binders, of which the following is a specification, the principle of the invention being herein explained and the best mode in which I have contemplated applying that principle, so as to distinguish it from other inventions.

My invention while inspirationally associated with loose-leaf binders generally, may be said to have more especial relation to the combination of members which together comprise the fastening contrivance proper.

The objects which the conception is alleged to effectuate, may be enumerated to comprise, the provision of a device which permits of successive or current insertions without in any wise disturbing such sheets as may already be embraced; which has few parts, is durable, slightly in appearance, readily manipulated, simple and hence economical of manufacture, and which furthermore adapts itself to satisfactory use without an inclosing cover by permitting a rigid projecting portion to be grasped by the hand.

The inventive conception is embodied in means which are hereinafter explained and variously combined in the claims, while the annexed drawing and particular description thereof together set forth in detail several certain means constituting my invention, the disclosed means however, being but some of various mechanical forms in which the principle of my invention may be applied.

Directing attention now to the drawing: Figure I is an elevation of one form of my invention showing the parts assembled. Fig. II is a top plan of Fig. I. Fig. III is an elevation of one part separated. Fig. IV is a vertical section taken longitudinally of another part. Fig. V is a perspective on a reduced scale showing my invention associated with a particular form of cover adapted to inclose the same. Fig. VI is a perspective indicating a use to which a modified form of my invention may be put. Fig. VII is an enlarged detail view showing a portion of one part in elevation. Fig. VIII is a vertical section similarly enlarged of the part seen in Fig. VI, in coöperation with another part.

The structure of my preferred form com-

prises a back or supporting member A and this is in fact an elongated flat strip of steel. Equally spaced and projecting upwardly from the member A are a plurality of rigid 60 prongs B. Each of these prongs is sharply pointed at its upper extremity b' and moreover just below such point is screw-threaded for a short distance as clearly designated by the character b^2 in Fig. III.

A complementary member or bar C likewise formed of steel and preferably nickel plated, is provided with a number of openings c' similarly located and spaced as the prongs B. A like number of hollow screw-caps D having interior complementary screw-threads d' project loosely through the openings c' . Their dislodgment is precluded by reason of the fact that their lower extremities d^2 are slightly upset.

As must now be apparent, the member C carrying the several members D may be placed over the extremities of the prongs B so as to rest upon and inclose them. Thereafter a successive rotation of the screw-caps 70 causes each in turn to engage the screw-threads b^2 and thus secure the members A and C with respect to each other.

In Fig. V the back member A is shown 85 sewn or otherwise inclosed within the confines of an inclosing cover F. I have found most satisfactory, a cover comprising two flaps f' of suitable dimensions, namely somewhat in excess as to length to that of the member A, and as to width somewhat in excess to that of the sheets intended to be embraced. This cover furthermore includes two intermediary strips f^2 and f^3 which are flexibly secured each to one flap and to each other along their opposite edges. The strip 90 f^2 is of a width equal to the total length of the prongs plus the projection of the screw-caps. The strip f^3 is of a lesser width, specifically such that it corresponds substantially with the width of the back member A which 95 it is intended to embrace as earlier suggested.

The modification seen in Fig. VI discloses the use to which my inventive binder may be put independently of an inclosing cover. 105 Such an applied use frequently answers in the case of newspapers G in public libraries for instance, where frequent substitution must needs be made and the binding of a comparatively small number of publications 110 is temporary. The use made of public reading facilities of this nature does not impose

a requirement for covers, in fact the identity of the particular publication is rather more readily discerned in practice in the absence of a cover. For the convenience of patrons, 5 however, while supporting a bunch of papers assembled as through the agency of my binder, it is desirable to provide some means permitting the whole to be firmly and comfortably grasped by the hand. To this end 10 the handle H is provided and may be secured to one extremity of the member A in any feasible manner.

My invention being thus described with sufficient thoroughness, what I desire to secure by Letters Patent and therefore claim specifically, is:

1. A loose-leaf binder comprising the combination of a base member, a pair of rigid prongs projecting therefrom each provided 20 near its free extremity with screw-threads, a clamping bar provided with openings spaced as said prongs, and a pair of complementary threaded screw-caps loosely seated in said openings respectively and 25 adapted to engage such prongs the outer sides of the caps being closed.

2. A loose-leaf binder comprising the combination of an elongated member, a plurality of substantially straight prongs projecting transversely therefrom, a bar having 30 upwardly recessed portions closed above, said portions being correspondingly spaced as and adapted to cover said prongs, and means operatively connecting said portions 35 and prongs for fixing said bar and the ends of said prongs with respect to each other.

3. A loose-leaf binder comprising the combination of a base-member, a plurality of prongs projecting therefrom, said prongs 40 being screw-threaded, a bar provided with openings correspondingly spaced as said prongs, and screw-caps pivotally mounted in said openings and adapted to engage said prongs said caps having their outer sides 45 closed.

4. A loose-leaf binder comprising the combination of a base-member, a plurality of prongs projecting therefrom, said prongs being screw-threaded near their extremities, 50 a bar provided with openings correspondingly spaced as said prongs and intersected by the latter, and screw-caps pivotally secured in said openings respectively and having their outer sides closed, said screw-caps being adapted to coöperate with said threads.

5. A loose-leaf binder comprising the combination of a supporting member, a plurality of prongs projecting therefrom, a clamping member provided with a plurality of apertures spaced as and adapted to be intersected by said prongs, and means movably supported upon said clamping mem-

ber for fixing the latter to said prongs, said means adapted to cover the extremities of 65 said prongs.

6. A loose-leaf binder comprising the combination of a base member, a plurality of prongs projecting upwardly therefrom and provided near their extremities with 70 screw-threads, a bar member provided with openings spaced as said prongs, and a corresponding number of complementary screw-caps loosely mounted in said openings, said caps being irremovable and adapted 75 to engage said prongs, and means involving the configuration of said caps for limiting their movement and that of said bar in the direction of said base member.

7. A loose-leaf binder comprising the 80 combination of a cover having two flaps and a plurality of intermediary strips, said flaps and strips being movable into different planes with respect to each other, a member secured to one of such strips and extending 85 parallel therewith, said member being provided with inwardly projecting prongs, a clamping bar having openings intersected by said prongs respectively, and fastening members mounted in said openings and 90 movable with respect thereto, said members adapted to coöperate with said prongs.

8. A loose-leaf binder comprising the combination of a pair of strips flexibly secured to each other, a pair of covers flexibly 95 secured to said strips respectively, a supporting member secured to one of said strips, a plurality of prongs projecting from said member, a clamping member provided with a plurality of openings spaced as and adapted 100 to be intersected by said prongs, and means for fixing said clamping member upon, and adapted to cover the extremities of said prongs.

9. A loose-leaf binder comprising the 105 combination of a pair of strips flexibly secured edgewise to each other one of said strips being wider than the other, a pair of covers flexibly secured edgewise of said strips respectively, a rigid supporting member inclosed by the narrower of said strips and provided with upright prongs projecting therethrough, said prongs being screw-threaded adjacent their upper extremities, a clamping member provided with a corresponding number of openings spaced as said prongs, and screw-caps movably secured in 110 said openings, said screw-caps being closed above and adapted to support said clamping member upon the extremities of said prongs. 115

Signed by me, this 31st day of March, 1913.

ROBERT J. HOPPINGER.
